GREASE GUN

Filed March 26, 1926

UNITED STATES PATENT OFFICE.

JAMES AUSTIN APPLEBY, OF LONDON, ENGLAND, ASSIGNOR TO C. C. WAKEFIELD & COMPANY LIMITED, OF LONDON, ENGLAND.

GREASE GUN.

Application filed March 28, 1926, Serial No. 97,621, and in Great Britain May 2, 1925.

This invention relates to grease-guns and has for its main object to provide means whereby a grease-gun nozzle-piece may be combined and used with a container or canister or drum in which the grease is sold. The term "grease-gun" is applied to a device which comprises a grease container so constructed that grease is ejected from the nozzle-piece by pressing the nozzle against the part to be lubricated, the nozzle constituting part of or being associated with a movable plunger or grease-pump by means of which the grease is ejected through the nozzle.

The container, canister or drum which comprises an element of the complete grease-gun is that type of receptacle in which the grease is sold and is usually made of thin material such as thin sheet metal and is preferably formed with a discharge outlet in one wall, preferably in the end wall. There may be within the container a sliding false bottom or follower piston as shown and described in British patent application No. 236,015.

According to the present invention there is combined with a grease-gun nozzle-piece of the type above described having means thereon for engaging it with a discharge outlet aperture in one wall of a grease container of the kind specified, a bridge-piece carried by or to be attached to the said nozzle-piece and so arranged, when the nozzle-piece is in position, as to bear on the container at a position or positions such that the thrust of the grease-gun nozzle-piece, when in use, is transmitted to and in the direction of the general plane of another wall or of other walls of the container that is or are transverse to that wall in which the outlet is situated. Preferably the bridge-piece is so formed that when the nozzle engages an outlet in an end wall of the container (for example, a cylindric container) the thrust is transmitted to the side walls thereof.

In the container to which the present invention is particularly applicable the cross-sectional area of the outlet aperture and of the engaging means between it and the nozzle-piece is of considerably smaller diameter than that of the end of the drum in which the outlet aperture is situated.

Conveniently the bridge-piece takes the

form of a spider surrounding the nozzle-piece and the free ends of the arms of said spider are shaped to engage the rim of the container. The bridge-piece may be adjustable along the length of the nozzle-piece and an adjustable abutment may be provided on said nozzle-piece to engage the bridge-piece in its adjusted position, so that the device can be used with containers having end flanges of different depths.

A preferred construction, embodying an example of the invention, is illustrated in the accompanying drawing, in which:

Figure 1 is a central sectional elevation of the complete assembled gun;

Figure 2 is a sectional end elevation on the line 2-2 of Figure 1, and

Figure 3 is a central sectional elevation of a portion of a modified form of gun.

The container 1 in which the grease is sold has a screw-nipple 2, at one end which is normally closed by a screw-cap or bung and inside the container is a sliding false bottom or follower piston 3 which follows the grease under atmospheric pressure as it is discharged through the gun, an air vent 4 being provided in the bottom of the container.

The grease-gun nozzle-piece is provided with a screw-socket 5 to engage the nipple 2 and comprises a barrel piece 6 having ports 7 which communicate with the interior of the container by way of the annular space 8. The plunger 9 is carried by a tube 10 to the end of which is secured the discharge nozzle 11 and a passage 12 through the plunger serves as the outlet port from the barrel and communicates with the aforesaid tube. A non-return ball-valve 13 serves to prevent entry of air when the plunger is returned under the action of the spring 14 which is housed in the guide member 15. If desired, the ball-valve may operate direct on the passage 12 in the plunger.

The exterior of the barrel piece is screw-threaded and has loosely mounted on it a spider 16 which constitutes a bridge-piece between the nozzle-piece and the rim of the container with which its arms engage. A nut 17 on the screwed barrel piece bears against the spider and holds it fast against the rim and forms an abutment to take the thrust of the gun. It will be seen that as the spider is loose on the barrel, the nozzle-

piece can be used with containers having flanges or rims of different depth, the nut 17 being adjusted along the barrel as required. In the example shown the arms 5 of the spider have suitably shaped claws 18 to engage the rim of the container.

In the modification shown in Figure 3 the end of the nozzle-piece is provided with a conical threaded boss 19 which can be 10 screwed into a plain hole in the end of a container, as shown. In this case the follower piston 3 may have a central recess 20 to enable it to move to the end of the container.

15 It will be seen that with the arrangements according to this invention the thrust due to the operation of the gun when the nozzle is forced against the part to be lubricated is transmitted to the side walls of 20 the container and it is therefore possible to utilize the comparatively thin walled containers in which the grease is sold, to form part of the gun itself as the thin end wall of the container to which the nozzle-piece is 25 secured is not required to withstand the thrust of the gun.

It will be understood that the end wall of the container or drum referred to in this specification is wider than the diameter of 30 the discharge outlet therein to which the grease-gun nozzle-piece is attached and the problem of relieving the thin end wall of the thrust of the gun in action only arises with such containers.

35 I claim:—

1. For a grease-gun, the combination with a nozzle-piece of the type necessitating the application to it of end pressure for operating the gun, and means thereon for engaging 40 it with a discharge outlet aperture in one wall of a grease container of the kind specified, of a bridge-piece carried by the said nozzle-piece and so arranged, when the nozzle-piece is in position, as to bear on the 45 container at a position or positions such that the thrust of the nozzle-piece, when in use, is transmitted to and in the direction of the general plane of another wall of the container that is transverse to that wall in 50 which the outlet is situated.

2. For a grease-gun the combination of a nozzle-piece having means for engagement with a discharge aperture in an end wall of a grease container wider in diameter than 55 the discharge aperture and a bridge piece carried by said nozzle-piece and adapted to bear upon the side wall of the container to relieve the said end wall of the thrust of the grease-gun in operation.

60 3. For a grease-gun the combination of a nozzle-piece having means for engagement with a discharge aperture in one end wall of a grease container being wider in diameter than the discharge aperture, and a 65 bridge-piece in the form of a spider sur-

rounding and carried by the said nozzle-piece, the free ends of the arms of the spider being adapted to engage the side walls of the container to relieve the said end wall of the thrust of the grease gun in 70 operation.

4. For a grease-gun having a nozzle-piece of the type necessitating the application to it of end pressure for operating the gun and adapted for use with a grease container 75 having a discharge aperture in one wall thereof, the combination with said nozzle-piece of means for engaging the nozzle-piece with said discharge aperture, and means axially adjustable on said nozzle-piece for 80 relieving said aperture and the wall in which it is set from the transmission of end thrust applied to the nozzle-piece.

5. For a grease-gun having a nozzle-piece of the type necessitating the application to 85 it of end pressure for operating the gun and adapted for use with a grease container having a discharge aperture in one wall thereof, the combination with said nozzle-piece of means for engaging the nozzle-piece 90 with said discharge aperture, a bridge-piece axially adjustable on said nozzle-piece and adapted to bear upon the side wall of the container and means in screw-threaded engagement with the nozzle-piece for maintaining the bridge piece in an adjusted position, in order to relieve the said aperture and the wall in which it is set from the 95 transmission of end thrust applied to the nozzle-piece. 100

6. For a grease-gun the combination of a nozzle-piece having means for engagement with a discharge aperture in one end wall of a grease container, having a peripheral rim, and being wider in diameter than the 105 discharge aperture, a bridge piece in the form of a spider surrounding and axially adjustable on the nozzle-piece, the free ends of the spider being adapted to engage the peripheral rim of the container, and an adjustable abutment on said nozzle-piece to engage the spider in order to relieve the end wall of the container of the thrust of the 110 grease-gun in operation.

7. For a grease-gun the combination of a 115 nozzle-piece having means for engagement with a discharge aperture in one end wall of a grease container having a peripheral rim, and being wider in diameter than the discharge aperture, and a bridge-piece in the form of a spider surrounding and carried by the said nozzle-piece, the free ends of the arms of the spider being adapted to engage the peripheral rim of the container to relieve the said end wall of the thrust of the 120 grease-gun in operation.

8. For a grease-gun the combination of an externally screw-threaded nozzle-piece having a screw-socket adapted to engage a 130 nipple in an end wall of a grease container,

said end wall having a peripheral rim, a bridge-piece comprising a spider surrounding and axially adjustable on the said nozzle-piece, the free ends of the arms of the spider being adapted to engage the peripheral rim of the container and a screw-threaded abutment on said nozzle-piece to engage said spider in order to transmit the thrust of the nozzle-piece in operation to the said peripheral rim whereby the said end wall is relieved of the thrust.

5 In testimony whereof I affix my signature.

JAMES AUSTIN APPLEBY.
